(57) **CLAIM**

The ornamental design for a convertible car organizer bag, as shown and described.

DESCRIPTION

FIG. 1 is a perspective view of the convertible car organizer bag with its lid closed;

FIG. 2 is a perspective view of the bag of FIG. 1 with its lid opened;

FIG. 3 is a right side view of the closed bag of FIG. 1;

FIG. 4 is a left side view thereof;

FIG. 5 is a top view thereof;

FIG. 6 is a bottom view thereof;

FIG. 7 is a front view thereof;

FIG. 8 is a back view thereof;

FIG. 9 is a top view of the open bag of FIG. 2; and,

FIG. 10 is a front view thereof.

The consistently-spaced broken lines in the drawings illustrate stitching that is part of the claimed design. The dot-dash broken lines in FIGS. 2 and 9 illustrating the interior compartments are included for the purpose of illustrating unclaimed subject matter and form no part of the claimed design.

1 Claim, 8 Drawing Sheets
